CLAIM

The ornamental design for a handlebar-mountable handbag, as shown and described.

DESCRIPTION

FIG. 1 is a perspective view of a handlebar-mountable handbag showing my new design;

FIG. 2 is a top plan view thereof with the strap broken away;

FIG. 3 is a front elevational view thereof with the strap broken away;

FIG. 4 is a right-side elevational view thereof with the strap broken away;

FIG. 5 is a rear elevational view thereof;

FIG. 6 is a bottom plan view thereof; and

FIG. 7 is a perspective view thereof mounted on bicycle handlebars, the broken lines showing of part of a bicycle is for illustrative purposes only and forms no part of the claimed design.

FIG-7

UNITED STATES PATENT AND TRADEMARK OFFICE
CERTIFICATE OF CORRECTION

PATENT NO. : Des. 322,714

DATED : December 31, 1991

INVENTOR(S) : Wayne Beiser

It is certified that error appears in the above-identified patent and that said Letters Patent is hereby corrected as shown below: On the title page, Item [56]

In the References Cited

The patent number of Lewis (D. 110,490) does not agree with the patent number cited by the Examiner in the application file.

In the Description

Fig. 4, lines 1 and 2, "with the strap broken away" should be deleted and replaced by --, the side opposite being a mirror image--.

Signed and Sealed this

Twenty-fourth Day of August, 1993

Attest:

BRUCE LEHMAN

Attesting Officer

Commissioner of Patents and Trademarks
